UNITED STATES PATENT OFFICE.

AZEL H. BELL, OF BELLE PLAINE, IOWA, ASSIGNOR OF ONE-HALF TO
FARIBAULT WIND MILL COMPANY.

GRINDING-MILL.

SPECIFICATION forming part of Letters Patent No. 239,701, dated April 5, 1881.

Application filed October 27, 1880. (No model.)

To all whom it may concern:

Be it known that I, AZEL H. BELL, of Belle Plaine, in the county of Benton and State of Iowa, have invented a new and Improved 5 Grinding-Mill, of which the following is a specification.

The object of this invention is to provide a mill especially designed for grinding feed, and operating with a reciprocating motion, and 10 adapted to be attached to the pump-rod of a windmill.

Figure 1 is a partly-sectional front elevation of the mill, with parts broken away to exhibit other parts. Fig. 2 is a plan of the mill. 15 Fig. 3 is a cross-section on line $x x$, Fig. 1.

Similar letters of reference indicate corresponding parts.

In the drawings, A represents the central grinding-plate, provided with suitable teeth 20 or corrugations, a, on each side, and having a lever, A', attached to its lower edge, whereby said plate A is connected with the pump-rod of a windmill (not shown) by suitable mechanism, and having, further, a segment or section removed from its upper edge, as shown 25 at b, for the admission of grain or other material to be ground.

B represents a horizontal shaft or bolt, on which is keyed or otherwise secured a flanged 30 sleeve or hub, C, to which latter the plate A is rigidly secured by the bolts B' or other convenient device.

On either side of the open plate A, with their toothed or corrugated faces in contact therewith, are the continuous outer grinding-rings, 35 D D, which are held in place by being bolted to the ratchet-plates E E, respectively, as shown at c c, the hubs of said ratchet-plates E E being set about either end of the sleeve 40 or hub C.

F is the case of the mill, held together by the bolts d d, having its periphery or edge closed at the top, as shown at f in Fig. 2, and open at the bottom.

45 Pivoted within the upper part of the case F on pins g, and hanging perpendicularly down with ends engaged in the peripheral teeth of the ratchet-plates E E, are pawls G, which are held in contact with the teeth of 50 said ratchet-plates E E by springs G' G', that are secured in sockets H. These pawls G

permit the ratchet-plates E and their attached grinding-rings D D to turn in the direction of the arrow, Fig. 1, but prevent their rotation in the opposite direction.

55 The grinding-rings D D are pressed against the central plate, A, or permitted to withdraw therefrom by turning up the nuts h h or the end of the shaft or bolt B against the washers m m, that press upon the ends of the hubs of the ratchet-plates E E, or by slackening said nuts h h, and thereby the mill is made to grind fine or coarse, as may be desired. M M are lugs, by means of which the mill is fixed upon suitable foundations for running.

65 The mill being put in motion, reciprocating or oscillating from right to left, and vice versa, the grain is fed through the hopper N into the opening b of the central plate, A, on either side, between the plate A and rings D D, and as the said plate A oscillates in the direction of the arrow, Fig. 1, the said grinding-plate A and rings D D move together in one direction, because of the friction caused between said plate and rings by the introduced grain. 70 Hence no grinding is accomplished, and consequently no power absorbed therefor; but on the return-stroke the plate A is moved, while the rings D D are prevented from moving by the engagement of the pawls G G in the teeth 75 of the ratchet-plates E E. Consequently the introduced grain is in some measure ground, and so on each stroke the rings D D are moved by and with the plate A, and held stationary 80 on the return-stroke by the pawls G G, whereby the grinding is effected. The plate A, it will be seen, makes a constant reciprocating motion, and the rings D D an intermittent 85 rotary motion. The grain or other material, as it is ground, falls from between the plate A and rings D D at the periphery of the mill. 90

95 By disengaging either one of the pawls G the corresponding ratchet-plate and ring will oscillate with the plate A, and therefore no grinding will be done on that side of the plate A--a condition that may be desirable in a light wind.

Having thus described my invention, what I claim as new, and desire to secure by Letters Patent, is--

100 In a grinding-mill, the combination, with the case F, carrying spring-pawls G, of the

central guiding-plate, A, having lever A', side teeth, *a*, and opening *b*, the supporting and adjusting bolt B, carrying the flanged sleeve C, the continuous outer grinding-rings, D D,
5 and the ratchet-plates E E, fixed to the rings at *c c*, and having their hubs set about either end of sleeve C, as shown and described, where-

by the mill is adapted to be operated and used as set forth.

AZEL H. BELL.
